HAIR DRIER

Reuben A. Olsen, Excelsior, Minn.

Application October 28, 1933, Serial No. 695,652

6 Claims. (Cl. 34—26)

This invention relates to hair driers, particularly of the air recirculating type, such as illustrated for instance in my copending application, Serial No. 646,380, filed December 9th, 1932, and the primary object is to provide in conjunction and combination with the drier mechanism, an air filtering unit, which will effectively cleanse the air so that it will not return to the patient's head laden with dust, dirt, germs, and other undesirable foreign matter, but will maintain the drying air in a sanitary and clean condition at all times. A further object is to provide an air filtering and purifying unit, for a hair drier, that is extremely simple in construction, and in which the filtering medium is a low cost yet efficient substance, and can be replaced by an inexperienced operator in a very short time and with little effort. These and other more detailed and specific objects will be disclosed in the course of the following specification, reference being had to the accompanying drawing, wherein:

Fig. 1 is a side elevation of a hair drier equipped with my invention.

Fig. 2 is an enlarged sectional elevation taken diametrically through the drier as shown in Fig. 1.

Fig. 3 is a perspective view of the filter unit employed in the drier, and showing a corner portion of the air purifying element as turned back to better illustrate the fastening means.

The drier construction proper follows, in general, the plan of that disclosed in my aforementioned application Serial No. 646,380, and includes an outer, substantially cylindrical shell or housing 4 which incloses and carries the drying mechanism, and is, in turn, adjustably supported on a suitable bracket or standard 5. Spaced within the housing 4 are two inner shell-like members 6 and 7, the latter of which may be referred to as a mask or inner dome, and it is the enclosure defined by this dome that receives or is placed over the head having the hair to be dried. The lower portions of the shell-like members 4, 6, and 7, are concentrically spaced with respect to each other to provide an inner annular chamber 8 and an outer annular chamber 9, and the lower ends of these chambers are closed by an integral flange portion 10 of the dome 7 which extends outwardly as shown in Fig. 2 to receive the lower end edges of the members 4 and 6.

The inner annular chamber 8 terminates above the dome 7 in a relatively large central chamber 11, in which operates a fan or blower 12. The

fan 12 is of the propeller or radial thrust type, and when operated functions to create a down draft of air about the dome 7 and into the interior thereof through a series of spaced holes 13. The air thus passing through the holes 13 or ports 13 to the interior of the mask 7 is not discharged from the unit, however, but is diverted back through openings 14 which are defined by short sleeves or collars 15 that connect the members 6 and 7 at spaced points so as to direct the return flow of air into the annular chamber 9 and without permitting it to in any way re-enter the annular chamber 8. Thus it will be seen that the air current created by the fan 12 will pass into the interior of the dome 7 at spaced points about the head having the hair to be dried, and after being briefly circulated through such hair is then withdrawn through the openings 15 at other spaced points, and from thence passes up through the annular chamber 9, all as indicated by the direction arrows.

The fan 12 is carried on and driven by the shaft 16 of an electric motor 17 rigidly secured in a cup like structure 18. This cup 18, together with a cap or dome member 19, are rigidly secured, as by screws 20 and spacer bars 21, to a ring 22 at the upper end of the shell 6. Heating elements 23 are arranged, preferably in the space between the bars 21 and cup 18, and their purpose is to heat the air passing downwardly through the annular passageway at this point and to the shell 7.

Immediately outwardly of the spacer rods 21, an annular opening or space 24 is provided between the upper end of the housing 4 and the outer edge of the dome 19. This space is arranged to snugly and detachably receive the filtering ring or unit, such as illustrated in Fig. 3, and this unit rests upon the ring 22 while a band or flange 25 at its upper edge is arranged to close the opening 24 to prevent outside air from passing into the housing at this point. I find it unnecessary to secure the filter unit in position, as its weight holds it down in place, but it is desirable to provide the flange 25 with a pair of small knobs 27 to facilitate lifting the unit out of the drier.

The filter unit comprises an annular skeleton framework including the band or rim 25, and a zig-zag, openwork frame unit 26 extending rigidly therefrom. The frame unit 26 serves as a support for the filtering material 28, which is wrapped about it, and this material preferably consists of a piece of conventional bandage 110

gauze, because such material is both sterile and sanitary and is also very economical to use. The gauze may be secured in place upon the skeleton frame in any suitable manner, but I have found it very practical and efficient to provide one of the frame bars, 26a, with oppositely directed prongs 29 upon which opposite ends of the gauze strip may be releasably attached.

It will now be readily seen and understood that with the filter unit in place and the drier in operation all of the air passing outwardly through the openings 14, from the hair being treated, will move in an annular stream or current up through the passageway 9 and will of necessity pass through the filtering material before being heated and returned to the patient's head, and this filtration of the air will result in the advantage first above noted.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. In a hair drier, an outer dome shaped housing having a head receiving perforate hood at its lower end, means within the housing for creating an air current and recirculating the same through said perforate hood, said housing having intermediate its ends an outwardly opening recess extending annularly thereabout, a circular skeleton frame removably disposed in said recess and when in place therein traversing the path of recirculated air travel, and a filter element carried by said skeleton frame.

2. In a hair drier, an outer dome shaped housing having a head receiving perforate hood at its lower end, means within the housing for creating an air current and recirculating the same through said perforate hood, said housing having intermediate its ends an outwardly opening recess extending annularly thereabout, a circular skeleton frame removably disposed in said recess and when in place therein traversing the path of recirculated air travel, and means for releasably securing a filtering cloth to said frame.

3. In a hair drier, an outer dome shaped housing having a head receiving perforate hood at its lower end, means within the housing for

creating an air current and recirculating the same through said perforate hood, said housing having intermediate its ends an outwardly opening recess extending annularly thereabout, a circular skeleton frame removably disposed in said recess and when in place therein traversing the path of recirculated air travel, and means for releasably securing a filtering cloth to said frame, said securing means comprising a plurality of prongs extending from the frame.

4. In a hair drier, an outer dome shaped housing having a head receiving perforate hood at its lower end, means within the housing for creating an air current and recirculating the same through said perforate hood, said housing being provided adjacent one end with an outwardly opening annular recess, a substantially cylindrical frame removably seated in said recess and when so seated traversing the path of recirculated air travel, and means for securing a filtering medium to said frame.

5. In a hair drier, an outer dome shaped housing having a head receiving perforate hood at its lower end, means within the housing for creating an air current and recirculating the same through said perforate hood, said housing being provided adjacent one end with an outwardly opening annular recess, a substantially cylindrical frame removably seated in said recess and when so seated traversing the path of recirculated air travel, a strip of filtering material wrapped circumferentially about the frame, and means for releasably engaging the strip ends to thereby detachably secure the material strip to the frame.

6. In a hair drier, an outer dome shaped housing having a head receiving perforate hood at its lower end, means within the housing for creating an air current and recirculating the same through said perforate hood, said housing being provided adjacent one end with an outwardly opening annular recess, a substantially cylindrical frame removably seated in said recess and when so seated traversing the path of recirculated air travel, and means for securing a filtering medium to said frame, said cylindrical frame being provided at one end edge with a rim adapted to close the annular recess so that when the frame is in place such rim will prevent air entering the housing through the recess.
